RETRACTILE CORDS

John Brown Cook, North Haven, Conn., assignor to
The Whitney Blake Company, Hamden, Conn., a cor-
poration of Connecticut

Filed Aug. 24, 1959, Ser. No. 835,769

3 Claims. (Cl. 174—69)

This invention relates to retractile cords suitable for use in various appliances, such as telephones, coffee pots and the like in which the appliance is moved from time to time, and in which the retractile cord is designed to take up the slack and avoid the unsightly appearance incident to the use of ordinary cords or jacketed conductors.

The term "cord" refers to one or more conductors, such as one or more lengths of flexible copper wire, which are enclosed within a jacket formed of suitable insulating material, to provide what is often referred to as a jacketed conductor. A "retractile cord" is a cord of helical shape and elastic, to the end that the helical cord will return to its original position after extension.

It is an object of the present invention to provide a retractile cord of greater compactness, that is, one in which the helix, when retracted, is shorter with respect to its extended length than in the case of the usual retractile cord.

According to this invention, the conductors of the retractile cord are arranged side by side in a plane which is generally perpendicular to the axis of the helix, thus providing a jacketed conductor which is ribbon-like or flat in appearance. In the usual multi-conductor type of retractile cord, the conductors are grouped in a circular or cable-like arrangement, which provides a jacketed conductor of circular cross section.

A further object is to provide a retractile cord which in its retracted form is in the shape of an upright helix of stable dimensions.

Another object is to provide a flat retractile cord which is capable of stacking itself and in which the cord is so shaped that the adjacent convolutions will nest into each other thus providing a cord of improved appearance.

Still another object is to provide a retractile cord of improved retractile properties.

According to the present invention, the inner portion of the jacketed conductor is crimped in a sinusoidal manner so that the alternate ridges and depressions will nest in the corresponding ridges and depressions of adjacent convolutions. Furthermore, this crimping substantially increases the extensibility over a flat retractile cord which is not crimped, and at the same time improves the retractile properties of the cord.

In the ordinary retractile cord wherein the jacket is in circular cross section, the retractile properties are, generally speaking, a function of the diameter of the helix with respect to the diameter of the jacketed conductor, the lower the diameter ratio, the greater being the resilience of the helix. As a result, the ratio of extensibility is generally of the order of 4 or 5 to 1.

By making an uncrimped flat retractile cord structure having an increased diameter ratio, the ratio of extensibility can be increased substantially since, in theory, the extended length would be the uncoiled length of the innermost element, which is to say, the product of the inner diameter, the number of convolutions, and pi. Actually however, this result cannot be obtained since the uncrimped flat configuration prevents the convolution from unwinding with the result that the ratio of extensibility is more of the order of 10 or 12 to 1.

However, I have found that by crimping the inner portion of each convolution, that the extensibility can be very considerably increased; as a matter of fact, in certain

2

diameter ratios, or proportions of helix diameter to jacket width, the cord is extensible to a length in excess of the theoretical but unattainable maximum indicated above, which is the function of the inner diameter of the helix, and that this increased extensibility is attained without introducing additional winding stresses in the cord.

A further object of my invention is to provide for a portable appliance or the like an improved storage arrangement so that the appliance and the cord will present a neat and self-contained appearance.

Other objects, features and advantages will become apparent as the description proceeds.

With reference now to the drawings in which like reference numerals represent like parts:

15 FIG. 1 is a side elevation of an appliance which incorporates a preferred embodiment of my invention;

FIG. 2 is a plan view of FIG. 1;

FIG. 3 is an elevation of the retractile cord of FIG. 1 in its retracted position;

20 FIG. 4 is a plan view of FIG. 3;

FIG. 5 is a section taken along line 5—5 of FIG. 4;

FIG. 6 is an elevation of the retractile cord in its ex-
tended position; and

FIG. 7 is a section showing a modification.

25 In FIGS. 1 and 2 an appliance such as a telephone instrument 10 is shown which comprises a base 11 and a hand set 12 which is removably received by a cradle 13. The hand set is electrically connected to the base 11 by a retractile cord 14 having an upper end portion 15, a lower end portion 16 and an intermediate portion 17 in the form of a helix. Although the end portions 15 and 16 may also be of the helical form to be described hereinafter, it is preferable to so manufacture the cord that these are straight and uncrimped as shown in FIGS. 1
30 and 2.

The retractile cord 14 rests on a platform 28 which projects outwardly from the base 11, and a suitable pin 19 may project upwardly from the base through the helix 17 in order to facilitate the stacking of the core by its own resilience when the hand set 12 is returned to its cradle 13.

35 As shown in FIG. 5, the retractile cord 14 comprises a plurality of metallic conductors which are arranged side by side in a common plane, four conductors 20, 21, 22 and 23 being shown for the purpose of illustration. The conductors are maintained in their side by side position and insulated from each other by a jacket 24 which provides a cord of ribbon like appearance which could be described as flat, except for the crimps 26. The conductors 20 to 23 may each be provided with individual jackets, not shown, in the customary manner, if desired. The jacket 24 is preferably an elastomer which will take a set in the helical and crimped form after suitable curing in order to provide a structure having the desired retractile or resilient properties. An example of a suitable jacket composition is set forth in co-pending application of Edgar L. Love, Serial No. 659,698, filed May 16, 1957, together with the curing characteristics thereof. Where individual jackets are 40 also provided these may be of a suitable resin or rubber like composition, or even of fabric, according to the usual practice in the jacketed conductor art.

45 The cord is extruded in straight or uncoiled form so that for a given section the length of all of the metallic conductors 20 to 23 is the same. Therefore, when the cord is wound into a helix wherein the general plane of the conductors of each convolution is substantially perpendicular to the axis of the helix, the inner cords 20, 21 and 22 will tend to buckle.

50 According to my invention, the inner portion 25 of the cord is provided with crimps 26 which take up the excess length of the inner cords in the jacket, the crimps pro-

viding both improved retractile properties and facilitating the stacking of the cord.

The crimps are of similar shape and are equidistantly spaced from each other so that when in contracted form the crimps of one convolution will nest with the crimps of adjacent convolutions. The crimps are applied both to the metallic conductors 20 to 23 and to the jacket 24 so that the insulation thickness will be substantially uniform. The crimping is done after the cord has been extruded and as it is being placed on a suitable mandrel for curing. The mandrel preferably is a grooved mandrel the inner portions of the grooves being also crimped so as to insure that the crimps in the jacket will be maintained during curing, to the end that the jacket is given a set both in the helical form and in the crimped form.

By virtue of the fact that the uncrimped length of the inner conductors is equal to the length of the outer conductor 23 the ratio of extensibility is considerably increased over that of an uncrimped flat cord which is extruded in helical form. In the latter instance, of course, the maximum theoretical extension length is the uncoiled length of the innermost conductor. However, as pointed out above, this degree of extensibility cannot be attained because the innermost filament of the helix tends to maintain the same radius of curvature with the result that the extensibility is limited to that which arises from the torsional flexure of the jacketed cord.

However, when the flat cord is crimped, as in the present invention, additional extension is provided by the fact that the crimped inner filament permits an unwinding or an increase in the radius of curvature.

As an example, the helix of FIGS. 3 and 4 may have an outer diameter of $2\frac{3}{8}$ inches, an inner diameter of $1\frac{3}{4}$ inches, and a convolution thickness of approximately .15 inch. A coil comprising $5\frac{1}{2}$ convolutions can be extended to $34\frac{1}{2}$ inches which is to be compared with a theoretical extension of 28 inches in an uncrimped flat coil, as determined by the inner diameter, and with a theoretical maximum of $38\frac{1}{2}$ inches if the outer filament is taken as controlling, or $36\frac{1}{2}$ inches if the length of the outer conductor 23 is taken as controlling.

The $34\frac{1}{2}$ inches of extension is about double the extension that can be attained without the crimping, where the extension is limited to the torsional deformation of the cross section of the cord. In other words, the additional unwinding action that is permitted by the crimping adds about 100% to the extension.

Furthermore, since this additional extension results in a flattening of the crimps, which represents either an elongation of the inner filament of the jacketed material or a flexural deformation of the cross section, the crimping in itself introduces an element of elasticity resulting in improved retractile properties.

Therefore, the present invention provides not only increased ratio of extensibility, but also an improvement in retractile properties. Furthermore, as pointed out above, the crimps provide a means of nesting the convolutions with respect to each other so as to provide a helix or stack which will retain its right cylindrical configuration of uniform diameter, thus providing a much neater appearance than if the crimps were not present.

The advantages of the present invention can be obtained with either a greater or lesser number of metallic conductors. However, the retractile properties of the cord are primarily a function of the size, shape and proportions of the jacket material and of the helix, with the result that the location of the one or more conductors within the jacket cross section does not affect the results obtained. In other words, where only two conductors are necessary, these two conductors could be conductors 22 and 23 or 20 and 21, or any other combination of the four conductors shown, the other two being eliminated. This is not to say that the width or the proportions of the jacket may not be varied according to the number of

conductors provided in the jacket, but, as a general proposition, I have found that a flat crimped cord provides a very definite advantage over the cord of circular cross section of the prior art. Where more than one conductor is required, the desired jacket cross section is best obtained by disposing the conductors in side by side relationship.

Although my improved retractile cord is of utility and various applications, as indicated above, it is of particular utility in connection with an appliance such as a telephone, coffee pot, clock, and the like in which the self-stacking characteristics of the cord may be utilized by providing a definite location for the cord when retracted, or for that portion of the cord which is retracted. In the application illustrated, the base of the telephone provides a platform for the reception of the cord. In the case of certain other appliances, however, as shown in FIG. 7, a bell-shaped base 30, of a lamp, for instance, is provided which provides a cavity 31 for the reception of a two conductor appliance cord 32 which is manufactured in accordance with the principles of this invention, the plug end 33 of the cord extending outwardly through a slot 34 in the base, and the unused portion of the cord resting on the table 35 or other surface on which the appliance itself is supported, the helix 32 being concealed by the bell-shaped base. In such an arrangement, the free or plug end of the cord can be either at the top or the bottom of the helix.

Although only a preferred embodiment of my invention has been shown and disclosed herein it will be understood that various modifications and changes can be made without departing from the scope of the invention as pointed out by the appended claims.

I claim:

- 35 1. A retractile cord comprising a plurality of parallel conductors aligned side by side, a jacket surrounding same to provide a flat, jacketed cord, said cord being arranged in a helix the axis of which is perpendicular to the general plane of the cord, and the inner edges of the convolutions being crimped to provide indentations which register with the indentations of adjoining convolutions so that said convolutions will nest within each other.
- 40 2. A retractile cord comprising a metallic conductor covered by a jacket formed of a cured elastomer, said cord being arranged in helical shape, and being flat in cross section, with the flatness of the cord being in a plane substantially perpendicular to the axis of the helix, the inner portions of said cord being crimped to permit a partial unwinding of the helix in order to provide increased extensibility.
- 45 3. A retractile cord comprising a plurality of metal conductors of uniform length aligned side by side in parallel relationship, a jacket formed of a cured elastomer surrounding same to provide a flat jacketed cord, said cord being arranged in a helical shape with the plane of said conductors approximately perpendicular to the axis of the helix, the innermost one of said conductors and that portion of the jacket which surrounds the same being crimped so as to permit elongation of said innermost conductor and its surrounding jacket when said helix is extended, the crimping of said jacket imparting resilience to said retractile cord when extended.
